THERMIONIC VALVE

Harry C. Reagan, Nicoma Park, Okla.

Application March 21, 1930. Serial No. 437,848

6 Claims. (Cl. 250—27.5)

My invention relates to thermionic valves or tubes, more particularly those used in the radio art.

The objects of my invention are to provide a device of this class which is new, novel, practical and of utility; which will be more efficient than tubes of present use; which will operate on a radio circuit of either A. C. or D. C. current; which will provide a positive means of either increasing or decreasing the electronic flow from the filament to the plate; which will prevent disturbances due a varying magnetic field when A. C. current is used; which will expedite the travel of electrons from the filament to the plate; which will reduce the negative space charge between the filament and the plate; which will provide an amplifier within the tube within the electronic field; the plate of which may be connected to and operate other radio apparatus; and which will be efficient in accomplishing all the purposes for which it is intended.

At the present time, the usual radio tube either operates only upon D. C. current, and if A. C. current is used a different type tube must be supplied. The usual tube necessitates the use of the exterior coil to regenerate or amplify the electronic flow from the filament to the plate. The control of the electronic flow from the filament to the plate is usually accomplished by varying the potential of the grid.

My tube may operate either on D. C. or A. C. current. It does not necessitate the use of exterior regenerating coils. I accomplish the positive control of the electronic flow from the filament to the plate by making the plate in two or more parts and varying the potential upon these parts, thus permitting one part to be made positive and another negative; or if desired all to be made positive in different degrees. It is obvious that by so constructing the plate, the different parts or divisions thereof may be connected to other elements of a radio circuit for their operation and for purposes other than those specifically stated herein.

I consider the construction of my filament a radical departure from that of the usual filament, and accomplish thereby new and useful results which are more fully brought out later herein.

With these and other objects in view as will more fully appear, my invention consists in the construction, novel features, and combination of parts hereinafter more fully described, pointed out in the claims hereto appended, and illus-

trated in the accompanying one-sheet drawing, of which,

Figure 1 is a top view of my invention;

Fig. 2 is an elevational view of the device with the plate laid out flat;

Fig. 3 is a top view showing the plate divided into two parts;

Fig. 4 is a schematic view of the filament; and

Fig. 5 is a schematic view showing a slightly different embodiment of the filament.

Like characters of reference designate like parts in all the figures.

It is understood that various changes in the form, proportion, size, shape, weight and other details of construction, within the scope of my invention may be resorted to without departing from the spirit or broad principle of my invention and without sacrificing any of the advantages thereof; and it is also understood that the drawing is to be interpreted as being illustrative and not restrictive.

One practical embodiment of the invention as illustrated in the drawing comprises:

A filament 1 of a suitable conductive material, which is best seen in Fig. 4. Said filament 80 comprises a heating and electron emissive element 2 in electrical contact with and surrounded by a coil 3. Said element 2 has one of its terminals connected with the positive side of the usual A battery or some other source of electrical energy while the terminal of coil 3 is connected to the negative side of said A battery or other source of energy. It will be obvious that in this manner said element 2 and coil 3 are connected in series. It may also be seen 90 that because the windings of said coil 3 are at right angles to the axis of and surround the magnetic field surrounding said element 2 will be at right angles to said element 2, the magnetic field generated by said coil 3. This will, of course, form a substantial magnetic cage around the heating element 2 and will thus neutralize the magnetic field produced by said elements 2 and 3. The effect will be the elimination of disturbances due to a varying magnetic field when A. C. current is used. As may be seen in Fig. 5 I show a slightly different embodiment of said filament 1. In this case, the heating element is constructed with two legs 4 and 5 connected electrically at their tops as 100 shown at 6. The coil 3 in this case emanates from the lower terminus of leg 5 and its spirals surround both of the legs collectively. Both the heating element and the coil are connected to the A battery or source of energy in a man- 110

ner similar to that in which the filament shown in Fig. 4 is connected. By constructing said filament in accordance with Fig. 5, I am able to increase the heating and emissive capacity of the filament without effecting the neutralization of the magnetic field. It may also be seen that by constructing said coil 3 of an electron emitting material and using said element 2 as a heating element and an electron emissive element, said coil 3 will act as a partial neutralizing force in reducing the temperature change in the element 3 and will produce a time lag in heat change. It will be obvious that the heating element may be made incandescent and the coil made of a material having low resistance, or they may both be made incandescent without effecting their action upon the magnetic field. It is also obvious that both the heating element and the coil or either selectively may be constructed of or coated with an electron emitting material.

Surrounding said filament 1, whether it be constructed in accordance with Fig. 4 or Fig. 5, is provided a usual grid 7, its terminal 8 adapted to connect in a usual manner to the usual grid circuit of the radio. Said grid 7 performs an office in my tube identical with the office performed by usual grids in tubes of known construction.

Surrounding said grid 7 I provide an amplifying or regenerating coil 9 having its terminal 10 connected electrically to the positive side of the usual B battery or other source of electrical energy, and having its upper end 11 connected to a plate 12. Said coil 9 is of a conductive material, and occupies a position between said grid 7 and said plate 12 and is thus directly in the electronic field. The terminal 13 of the plate 12 may be connected with the plate circuit in any usual manner. It is well known to those versed in the art that any variation in the grid potential will cause a change in the electron flow from the filament to the plate, and that this in turn will create a variable potential and current flow from the positive source of current through the plate circuit. In placing said coil 9 as above described, I accomplish a two-fold result. Said coil 9 adds the effect of the varying potential flowing through it to that of the grid, thus amplifying the trigger action. Said coil 9 also due to its positive potential and due to its location directly within the electronic field, acts to reduce the negative space charge between the grid 7 and the plate 12. This will of course expedite the electronic flow from the filament to the plate.

The plate shown in Fig. 1 is usual and is not claimed by this inventor as invention. However in Figs. 2 and 3 I show a different embodiment of the plate structure. In this case the plate 12 comprises two sections 14 and 15, neither of which are in electrical contact with each other, there being openings between them as shown at 16. The terminal 11 of coil 9 is attached to section 14 of plate 12, while the terminal 13 leads from the other section 15 of plate 12. The advantages gained by so constructing plate 12 are numerous.

It is evident that by varying the potential in said sections 14 and 15, I may cause electrons to flow to one section and not to the other. This will have a pronounced result in that the electrons will be emitted from the section which is supplied with the highest potential.

I claim a vacuum tube having a filament

by making one a positive plate and the other negative. I may also in the same manner make one positive and the other super-positive, thus absolutely controlling the electronic flow from the filament to the plate or any section thereof. It is to be understood that I reserve the right to form said plate 12 of any desired number of sections in which case each section but the ones to which said coil 9 is connected will be supplied with one of the terminals 13. In dividing said plate 12 into sections, I am enabled to divide the amount of current flowing through plate 12, thus connecting the sections electrically to different apparatus of a radio. There are of course various circuits to which the above described valve may be applied to an advantage, other than the usual radio circuits. It is to be understood that the device as described will be enclosed by a usual envelope 17.

Obviously, the invention is susceptible of embodiment in forms other than that which is illustrated in the accompanying drawing and described herein, and applicable for uses and purposes other than as detailed, and I therefore consider as my own all such modifications and adaptations and other uses of the form of the device herein described as fairly fall within the scope of my invention.

Having thus described my invention, what is claimed and desired to be secured by Letters Patent, is:

1. In a thermionic valve, a filament, a grid surrounding said filament, a regenerating coil surrounding said grid, and a plate surrounding said coil, one terminal of said coil being connected electrically to and in series with said plate.
2. Organization as described in claim 1, in which said filament comprises a central member emitting magnetic waves in a substantially horizontal plane, and a surrounding member emitting magnetic waves in a plane substantially at right angles to said first mentioned plane.
3. Organization as described in claim 1, in which said plate comprises a plurality of separate sections each having a terminal for connecting a radio circuit, some of said sections connected electrically to said regenerating coil, said sections adapted to receive different potentials for controlling the electronic flow from said filament to each respective section of said plate.
4. Organization as described in claim 1, in which said regenerating coil has one of its terminals electrically connected to an external circuit, and its other terminal connected to the plate, and in which said regenerating coil is in series with said plate.
5. Organization as described in claim 1, in which the regenerating coil is in series with the plate and is between the source of current and the plate.
6. Organization as described in claim 1, in which said regenerating coil has one of its terminals electrically connected to an external circuit, and its other terminal connected to the plate, and in which said regenerating coil is in series with said plate, and between said plate and the source of electrical energy.

HARRY C. REAGAN.
